(57) **CLAIM**

I claim the ornamental design for an air control damper for a barbecue grill or smoker, as shown and described.

DESCRIPTION

FIG. 1 is a top perspective view of an air control damper for a barbecue grill or smoker showing my new design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a front elevational view thereof; and,

FIG. 7 is a rear elevational view thereof.

My air control damper for a barbecue grill or smoker is characterized by its circular hole air vents that are arranged in a circular pattern around the unit, bent end tab for easy turning, and spring elevated mounting bolt.
